(57) **CLAIM**

The ornamental design for a connector assembly, as shown and described.

DESCRIPTION

FIG. 1 is a perspective view of the connector assembly showing our new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines are included for the purpose of illustrating environmental structure and form no part of the claimed design.

The connector assembly is shown with a symbolic break in its length, represented by a curved break line. The appearance of any portion of the article between the break line forms no part of the claimed design.
